UNITED STATES PATENT OFFICE.

FOREST CHENEY, OF CHICAGO, ILLINOIS, ASSIGNOR TO CHENEY TALKING MACHINE CO., OF CHICAGO, ILLINOIS, A CORPORATION OF ILLINOIS.

LEVER-COUNTERBALANCE.

1,387,833.

Specification of Letters Patent. Patented Aug. 16, 1921.

Application filed November 26, 1919. Serial No. 340,814.

To all whom it may concern:

Be it known that I, FOREST CHENEY, a citizen of the United States, residing at Chicago, in the county of Cook and State of Illinois, have invented certain new and useful Improvements in Lever-Counterbalances, of which the following is a specification.

While applicable in principle to any situation where movement of one body toward another is to be resiliently opposed, the embodiment herein selected for purposes of illustration has been designed primarily for counterbalancing the hinging cover of a cabinet, for example, the cabinet of a talking machine.

The invention has for its primary object to produce a simple and efficient lever counterbalance that may readily be applied within the limited space afforded by the inside walls of the structure, with the end of the counterbalancing lever connected through a link with the cover to be controlled; subordinate objects incident thereto relating to the provision of anchorage means that will receive one end of a helical spring while the other end of said spring is acting upon the inner end of the lever; also to render such anchoring means conveniently adjustable from the exterior of the mounting; and also to provide details of construction that will be particularly advantageous in realizing these several objects aforesaid.

In carrying out the invention, according to the present illustrative embodiment, a combined housing, support, and fulcrum member is provided, preferably in the form of a cylindrical shell, with a surrounding flange through which to attach it, a controlling lever working through a slot in the shell being fulcrumed upon a stud carried within the shell; an anchoring support being provided within the shell in position to receive and sustain one end of a coiled spring while the other end is acting upon the lever; the anchoring member being preferably secured by the fulcruming stud in a manner to permit its adjustment about the latter and having an arm protruding beyond the shell through which to develop such adjustment for the purpose of regulating the tension of the spring; and a novel construction of securing means being provided to hold the anchoring member to its adjustment.

The invention consists in the novel features of construction of certain of the parts

above named, as well as their organization or combination, hereinafter pointed out in the claims.

In the accompanying drawing—

Fig. 1 is a sectional view showing the application of a pair of lever counterbalances constructed in accordance with the present invention.

Fig. 2 is a section of the same in a plane at right angles to the section of Fig. 1, and on an enlarged scale.

Fig. 3 is a detail view of a portion of Fig. 2 with the head of the casing removed to disclose the parts within.

Fig. 4 is a sectional view taken in the plane of line 4—4 of Fig. 3.

Fig. 5 is a view of a portion of Fig. 2 showing the application thereto of a tool through which adjusting movement may be imparted to the anchorage member of the spring.

Fig. 6 is a detail view of the jaw of the securing grip of the anchoring member; and

Fig. 7 is a detail of the tool shown in Fig. 5.

The device is intended for resiliently supporting one member upon another, such, for instance, as the cover A over the well B of a talking machine cabinet, the device being designed particularly for application to the side walls b of such a cabinet.

1 represents a cylindrical shell or casing having an attaching flange 2 and a closed head 3. Fulcrumed upon a stud 4 centrally located in the head 3 is the balancing lever 5 which works through a slot 6 in the cylindrical wall of the shell through an arc which is sufficient to follow movements of the parts between the full line position and the dotted line position shown in Fig. 2.

Arranged within the shell 1 concentrically with the stud 4 is a balancing coil spring 7, preferably of helical form, having its anchoring and controlling ends each at the circumference of the coil. These ends are provided with hooks 8 and 9 through which they, respectively, engage the inner end 5^a of the balancing lever 5 and the end 10^a of an anchoring member 10. The anchoring member is mounted upon the same stud 4 with the balancing lever 5, and it is adjustable concentrically with said lever or with the coil spring in order to regulate the tension of the spring. To impart this tension-regulating movement to the anchoring mem-

ber 10, said member has an arm 10^b protruding beyond the cylindrical wall of the shell through a slot therein, and said anchoring member is provided with a binding 5 screw 11 through means of which it can be held to its adjustment. Screw 11 is fixed against displacement in the head 3 of the shell where it is conveniently accessible to tighten it upon the anchoring member after 10 the latter has received its adjustment; and to insure its control over the anchoring member its inner end is threaded into a jaw 12 which lies on the opposite side of the anchoring member from the head 3 so that by 15 tightening the screw the anchoring member may be firmly gripped between the head and the jaw. The jaw may have its gripping face suitably roughened or knurled as suggested in the drawing; and for economy in 20 assembling, and also to afford a spacing means between the swinging lever 5 and the fulcruming member 10, said jaw 12 is mounted upon the stud 4, which serves in common for the anchoring member and the 25 lever.

To adjust the tension of the spring, it is merely necessary to displace the arm 10^b circumferentially of the shell. For convenience in accomplishing this a tool C is provided in the form of a spanner having an 30 arcuate portion C' adapted to fit the wall of the shell, and a finger C² adapted to engage the arm 10^b while the arcuate portion is being guided upon the cylindrical wall 35 of the shell. Adjustment is accomplished by releasing the screw 11 while holding the tool against the arm of the anchoring member, displacing the arm circumferentially of the shell until the supported member is 40 sustained by the balancing arm, and then tightening the screw to hold the parts to their adjustment.

Since the mounting shell 1 is located eccentrically to the hinge of the member A 45 to be supported, the balancing lever 5 is connected to said member through means of a link 13 that compensates for digression of the arcs through which the end of the lever and the point of attachment of the supporting member must swing.

I claim:

1. In a lever counterbalance, a lever, a fulcrum for said lever, a mounting carrying 55 said fulcrum, an anchoring member carried by said mounting, and a coil spring having its respective ends connected with the lever and said anchoring member; said anchoring member being adjustable about the lever fulcrum and having means for holding it to 60 its adjustment.

2. In a lever counterbalance, a lever, a fulcrum for said lever, a mounting carrying 65 said fulcrum, an anchoring member carried by said mounting, and a coil spring having its respective ends connected with the lever

and said anchoring member; said anchoring member being adjustable about the fulcrum of the lever and having an arm protruding beyond the mounting through which to impart its adjustment. 70

3. In a lever counterbalance, a lever, a fulcrum for said lever, a mounting carrying said fulcrum, an anchoring member carried by said mounting, and a coil spring having its respective ends connected with the lever and said anchoring member; said anchoring member lying against the mounting, being adjustable about the lever fulcrum, and having means for holding it to its adjustment; and said holding means comprising 80 a screw passing through the mounting and through the anchoring member, and a jaw on the opposite side of the anchoring member receiving said screw.

4. In a lever counterbalance, a lever, a fulcrum for said lever, a mounting carrying said fulcrum, an anchoring member carried by said mounting, and a coil spring having its respective ends connected with the lever and said anchoring member; said anchoring member lying against the mounting, being adjustable about the lever fulcrum, and having means for holding it to its adjustment; said holding means comprising a screw passing through the mounting and 90 through the fulcrum member and a jaw on the opposite side of the fulcrum member receiving said screw; and said jaw comprising an arm carried by the fulcrum.

5. In a lever counterbalance, a lever, a fulcrum for said lever, a mounting carrying said fulcrum, an anchoring member carried by said mounting, and a coil spring having its respective ends connected with the lever and said anchoring member; said anchoring member lying against the mounting, being adjustable about the lever fulcrum, and having means for holding it to its adjustment; said holding means comprising a screw passing through the mounting and 100 through the fulcrum member, and a jaw on the opposite side of the fulcrum member receiving said screw; and said jaw comprising an arm carried by the fulcrum and positioned intermediate of the lever and the anchoring 110 member.

6. In a lever counterbalance, the combination of a cylindrical shell having an axial stud, a lever working through the cylindrical wall of said shell and fulcrumed upon 120 said stud within the shell, an anchoring member mounted upon the stud within the shell, and a coil spring within the shell having its respective ends connected with the lever and with the anchoring member. 125

7. In a lever counterbalance, the combination of a cylindrical shell having an axial stud, a lever working through the cylindrical wall of said shell and fulcrumed upon 130 said stud within the shell, an anchoring

member mounted upon the stud within the shell, a coil spring within the shell having its respective ends connected with the lever and with the anchoring member, and a 5 clamping jaw for the anchoring member also mounted on said stud and located between the lever and the anchoring member.

8. In a lever counterbalance, the combination of a cylindrical shell having an axial 10 stud, a lever working through the cylindrical wall of said shell and fulcrumed upon said stud within the shell, an anchoring member mounted upon the stud within the

shell, and a coil spring within the shell having its respective ends connected with the 15 lever and with the anchoring member; said anchoring member being adjustable upon said stud and having an arm protruding through the cylindrical wall of the shell through which to impart its adjustments. 20

Signed at Grand Rapids, Michigan, this twelfth day of November, 1919.
